WRIGHT R. CARTLEDGE, OF BALTIMORE, MARYLAND, ASSIGNOR TO CHESTERMAN AND STREETER, INC., OF PHILADELPHIA, PENNSYLVANIA, A CORPORATION OF PENNSYLVANIA.

ABDOMINAL BELT.

1,190,722.

Specification of Letters Patent. Patented July 11, 1916.

Application filed December 4, 1915. Serial No. 65,051.

To all whom it may concern:

Be it known that I, WRIGHT R. CARTLEDGE, a citizen of the United States, residing in the city and county of Baltimore, State of Maryland, have invented a new and useful Abdominal Belt, of which the following is a specification.

My invention consists of an abdominal belt adapted to be adjusted in depth at its front according to the requirements of the abdomen. To this end, there is added to the belt a movable section or member which may be lowered thereon, and means for holding said section or member in the position to which it is adjusted.

It consists also in providing the belt with means forming a closure for the opening caused by the ends of the belt at the rear thereof, the same serving also to cover the lacing, etc., of said ends, and preventing said lacing, etc., from contacting directly with the body of the wearer.

The invention is satisfactorily illustrated in the accompanying drawing, but the important instrumentalities thereof may be varied, as long as they are included in the scope of the claims.

Figure 1 represents a perspective view of an abdominal belt embodying my invention. Fig. 2 represents a top edge view thereof. Fig. 3 represents an elevation of a portion of the front of the belt. Fig. 4 represents an elevation of a portion of the front of the movable section or member of the band.

Similar numerals of reference indicate corresponding parts in the figures.

Referring to the drawings, 1 designates an abdominal or elastic belt which excepting the features of my invention applied thereto is well known in the art.

2 designates a section or piece of a band of elastic material which is placed vertically slidably on the front of the belt 1 and connected at its ends with what may be termed the side of said belt by the lacings 3 and eyelets 4, the straps 5 and buckles 6, there being in the present case a greater number of eyelets on one side of the band 1, than in the adjacent end of the section 2, and a greater number of buckles on the other side of the belt 1, than of straps on the adjacent end of said section, it being evident that said section may be let out and taken in and lowered on the belt 1 to a greater extent than that

shown in Fig. 1, and so increase the depth of 55 the belt and thereby adjust the front of the latter according to the anatomy of the abdomen and to be properly fitted and tightened thereon with the proper pressure while also imparting the proper pressure to the 60 relative portion of the belt, and consequently to the abdomen where said belt contacts.

On the belt 1 at the center thereof is the series of tapes or straps 7 arranged horizontally thereon one below the other and so secured thereto that their ends are left free 65 for tying purposes.

On the section 2 at the center thereof is the tape or strap 8 arranged horizontally thereon and so secured thereto that the ends 70 are left free for tying purposes. It will now be seen that when the belt is placed on the abdomen and the section 2 adjusted in depth thereon the tape 8 thereon is tied and bow-knotted, or otherwise secured to the proper 75 tape of the series of tapes 7 on the belt 1, whereby the section will be nicely connected with the band and retained in its adjusted position thereon. When the section 2 is adjusted to the position shown in Fig. 1, the 80 tapes 8 of the latter are brought to the upper most tapes 7 of the section 1 and secured thereto. Should said section 2 be lowered, the tapes 8 are secured to the second line of 85 tapes 7. The section 2 may be lowered to greater extent to the third or fourth lines of tapes 7, as the case may be, and either of said lines of tapes 7 may be tied to the tapes 8.

The bow knots of the tapes 7 and 8 appear on the exterior of the section 2, as in Figs. 90 1 and 2.

It will be noticed that as the section 2 is lowered, the tapes 8 follow the same, but the tapes 7 will be uncovered, hence they present them successively for connection with 95 said tapes 8.

An additional connection for the section with the band is provided by the tape or straps 9 on the inner side of the center of said section, the same being adapted to be 100 tied to either of the tapes 7 of the belt below the tape 8 of the section.

To the back of the belt on one side of the laced-placket opening 10 there is secured by the stitches 11 one end of the flap 12 which 105 crosses the opening of the placket and the lacing and eyelets of the walls thereof so as to form a closure for said opening and a

cover for the eyelets and lacing of the placket thus guarding the body of the wearer from contact therewith.

6 The end of the flap opposite to the stitches 11 is disconnected from the contiguous portion of the belt whereby said flap may be let out or taken in relatively to the extent of the width of the opening 10 in the adjustment of the placket to the body of the 10 wearer, but in order to hold said disconnected end in adjusted position on the belt, I employ the tape 13 which is reeved through a plurality of eyelets 14 on the flap and a plurality of eyelets 15 on the belt and properly drawn taut and its ends are bow-knotted or otherwise secured as at 16 on the exterior of the belt, whereby they are convenient of access. The eyelets or openings 14 in the 15 flap and on the belt are separated so that the tape 13 extends flat from one eyelet to the other in each respective part, whereby the flap is held flat on said portion of the placket in its adjustments.

20 Having thus described my invention what I claim as new and desire to secure by Letters Patent, is:—

25 1. In an abdominal belt, a band overlying

the front portion of said belt, means for adjustably connecting the ends of said band to said belt whereby a vertical adjustment of 30 said band is provided, and means for holding said band in its adjusted position.

2. An abdominal belt having a placket thereon and means on the latter for securing and adjusting the same, and a flap member adapted to close the opening of said placket, the same being connected at one end with a side of said placket, passing said opening and overlapping freely the other side of said placket, and a securing and 40 adjusting tape-like member reeved through said free end of the flap member and the adjacent portion of the belt adjacent to said placket, said free end of the flap member and said adjacent portion of the placket of the belt having each therein a plurality of registering separated eyelets for the passage therethrough of said tape-like member, whereby said flap is held flat on said adjacent portion of the belt.
